UNITED STATES PATENT OFFICE

BERT G. LARRABEE, OF HOUSTON, TEXAS

DESIGN FOR A COMBINED WRITING AND SMOKING STAND

Application filed August 29, 1929. Serial No. 32,608. Term of patent 14 years.

To all whom it may concern:

Be it known that I, BERT G. LARRABEE, a citizen of the United States, residing at Houston, in the county of Harris and State of Texas, have invented a new, original, and ornamental Design for a Combined Writing and Smoking Stand, reference being had to the accompanying drawing, forming a part hereof.

The figure is a perspective view of a combined writing and smoking stand, showing my new design.

I claim:

The ornamental design for a combined writing and smoking stand, as shown.

In testimony whereof, I hereunto affix my signature.

BERT G. LARRABEE.
